MOUNTS FOR TRANSPARENCIES

Robert Thomas Lewis, London, England, assignor of

one-half to Lucy Lewis, London, England

Filed Nov. 1, 1960, Ser. No. 66,626

Claims priority, application Great Britain Nov. 10, 1959

2 Claims. (Cl. 40—152)

This invention relates to mounts for transparencies. According to this invention the mount comprises an inner transparent sleeve and an outer frame, the sleeve being slidable into the frame and means being provided for removably holding the sleeve in the frame. Preferably the said means comprises a resilient flange on the surface of the sleeve adapted to engage an internal flange on the frame.

One form of mount made according to this invention is illustrated in the accompanying drawing, wherein:

FIGURE 1 is a front elevation of the sleeve with the transparency partly inserted,

FIGURE 2 is an end elevation of the sleeve,

FIGURE 3 is an exploded rear view of the frame,

FIGURE 4 is a front elevation of the mount with the sleeve partly inserted, and

FIGURE 5 is a fragmentary end section to an enlarged scale showing the means for holding the sleeve in the frame.

Referring to the drawing, the sleeve comprises a front panel 1 and a back panel 2 having a turn down flap 3 all integrally formed from a strip of transparent cellulose acetate, appropriately creased. A transparency 4 to be protected can be slidden into the sleeve from either side, both being open. A cardboard frame into which the sleeve is placed for viewing purposes comprises a front panel 5 and back panel 6 of the same size, both having central windows 7 which are aligned when the two panels 5 and 6 are brought together. The upper marginal portion of the front panel 5 has on its rear face a strip of cellulose acetate 8 projecting upwards forming a catch. The two panels 5 and 6 are permanently united along their side marginal portions by adhesive or stitches, distance strips 9 being provided between them so as to provide a clearance for the accommodation of the sleeve. The top and bottom edges of the frame panels are not united.

In use, the sleeve with the transparency in it is slidden into the frame from the bottom as shown in FIGURE 4 until the edge of the turn down flap 3 is beyond the catch 5 whereupon it is drawn down again slightly. The resilience of the flap 3 causes it to engage behind the catch 8 which holds the sleeve snugly in the frame in the correct

2

position. The sleeve is removed by pushing it up through the top of the frame.

Although the invention has been described with reference to a cellulose acetate sleeve and a cardboard frame, 5 other suitable materials can be used provided that the sleeve is transparent and a suitable engaging flap can be provided. The frame can be made of metal or plastics material and instead of the cellulose acetate catch 8, other forms of catch can be provided, for example, a wire or 10 nylon line or a slit provided in the material of the frame, or a projecting rib formed integrally with the frame or attached to it providing a ledge for the edge of the flap 3.

Among the advantages of this invention is that the transparencies can be stored in their protective sleeves and 15 only placed in the frames for viewing purposes thereby saving space and the expense of numerous frames.

What I claim and desire to secure by Letters Patent is:

1. A mount for a transparency comprising in combination, a frame including a front panel and a back panel 20 each of which is provided with a window, said windows being in alignment, said panels being secured one to another in face to face relationship and spaced apart by distance strips arranged between the two panels along the marginal portions of the opposite sides of the frame 25 whereby the space between the panels is open from top to bottom for the reception of a sleeve, a horizontal catch disposed between said panels extending above the said windows, and a removable sleeve removably disposed in the said space, said sleeve comprising a strip of transparent material open at both ends and folded to form front and back panels and a turned down flap on one of said panels adapted to engage the said horizontal catch when the sleeve is in the said space.

2. A mount for a transparency according to claim 1, 35 in which the catch is on the rear face of the marginal portion of the front panel and projects upwardly at an angle to said rear face.
